(57) **CLAIM**

The ornamental design for a pipe flange separator, as shown and described.

DESCRIPTION

FIG. 1 is a perspective view from the bottom, rear, right of a pipe flange separator of my new design;

FIG. 2 is a bottom plan view thereof;

FIG. 3 is a top plan view thereof;

FIG. 4 is an elevational view thereof from the right;

FIG. 5 is an elevational view thereof from the left;

FIG. 6 is an elevational view thereof from the rear;

FIG. 7 is an elevational view thereof from the front; and,

FIG. 8 is an elevation view thereof from the right, the broken lines showing environment only that form no part of the claimed design.

1 Claim, 8 Drawing Sheets
